RETRACTABLE SUPPORT FOR FLATIRONS

William H. Ginder, Haddonfield, N. J., assignor
to Proctor & Schwartz, Inc., Philadelphia, Pa.,
a corporation of Pennsylvania

Application February 21, 1936, Serial No. 65,139

8 Claims. (Cl. 38—79)

This invention relates to devices for supporting a flat-iron away from an operating surface whenever the iron is not being used. The principal object of the invention is to provide an improved 5 device of this character embodying certain novel features which render the device a marked improvement over prior devices of the same class.

Another object of the invention is to provide a 10 device of this nature wherein the supporting means is contained within a recess or housing at the rear of the iron during periods of non-use of the supporting device, thereby improving the appearance of the iron and positioning the supporting means in a manner such that it will not 15 interfere with the normal functioning or use of the iron.

A further object of the invention is to provide 20 a flat-iron supporting device comprising a plurality of arms which are movable foldably into a transverse position at the rear of the iron and which are movable extendibly into longitudinal position beneath the iron to serve as a support therefor.

Other objects and features of the invention will 25 appear hereinafter. The invention may be clearly understood by reference to the accompanying drawing illustrating a specific embodiment of the device.

In the drawing:

30 Fig. 1 is a side elevational view of a flat-iron embodying the invention, certain parts being shown in section for the purposes of illustration;

Fig. 2 is a sectional view taken along line 2—2 of Fig. 1;

35 Fig. 3 is a fragmentary plan view of the iron-supporting mechanism;

Fig. 4 is a detail view of a part of the actuating mechanism for the device; and

40 Fig. 5 is an exploded perspective view of certain parts of the supporting device.

Referring first to Fig. 1, there is shown a flat-iron comprising, as usual, a sole plate 1, a cover 2, front and rear legs 3 and 4, respectively, extending upward from the cover and supporting the handle 5. In accordance with the present invention, there is provided a hood 6 which is preferably formed integrally with the cover and which extends rearward beyond the body of the iron, as clearly shown. This hood provides a recess 7 within which the iron-supporting mechanism is normally positioned. It will be understood, of course, that a recess or housing for this purpose may be provided in any suitable manner other than that specifically illustrated.

55 In further accordance with the invention, there

are provided at the rear of the sole plate 1 a pair of similar members 8 (see Fig. 5), these members preferably being seated within a recess 9 provided in the rear portion of the sole plate. The members 8 may be secured to the sole plate 5 in any suitable manner, for example, by means of screws 10 (see Fig. 3). As shown clearly in Fig. 5, each of the members 8 comprises an extending bifurcated bearing block 11 which is adapted to rotatably hold an end portion of a 10 transverse shaft 12, the shaft being held in place by pins 13a (see Fig. 3) passing through the holes 13. Thus, the shaft 12 is transversely disposed at the rear of the iron and is rotatably mounted in the bearing blocks 11. 15

Each of the members 8 also comprises a curved cam element 14 having a cam slot 15 therein. At its upper end, the slot 15 extends transversely inward, as shown clearly at 16.

The iron-supporting device further comprises 20 a pair of L-shaped arms 17 which are normally disposed in folded transverse position within the hood 6, as clearly shown in Figs. 2 and 3. The end portions of these arms adjacent the iron are rotatably carried at the ends of shaft 12. As 25 shown in Fig. 5, each end of shaft 12 is formed to provide a head 18 having an opening 19 within which the portion 20 of the associated arm 17 is rotatably seated. Shoulders 21 on the arm 17 prevent longitudinal movement of the arm through 30 opening 19. Adjacent the inner shoulder, there is provided on the arm 17 a lug or extension 22 having a flat surface, the purpose of which will appear later. At the end of the arm 17, there is provided a small crank 23 including a pin 24. 35 The pin 24 seats in slot 15 of the cam element 14 and is adapted to ride in the slot, as will be more fully explained later.

At its central portion, the shaft 12 is provided with a crank arm 25 (see Fig. 4) to which there 40 is attached an actuating arm 26 by means of a bifurcated yoke element 27. Thus, arm 26 is pivotally attached to crank 25 at 28 (see Fig. 4). The rear leg 4 is hollow and the arm 26 extends 45 upwardly therethrough, as shown in Fig. 1, and is attached to the rear end of a lever 29. The handle 5 is hollow and the lever 29 extends therethrough and is pivotally mounted at 30. The front end of lever 29 is formed so as to be engageable by the nose 31 of a pivoted actuating 50 device 32 having a finger portion 33. The device 32 is pivotally mounted at 34. A coil spring 35 is also housed within the rear leg 4 and has one end fastened at 36 to a turned-up lug on the cover. 55

while the opposite end of the spring is attached at 31 to the rear end of lever 29.

It will be seen that spring 35 urges the lever 29 in a clockwise direction, as viewed in Fig. 1. In this manner, the spring acts through arm 26 and crank 25 to maintain shaft 12 in a position such that the supporting arms 17 are maintained in inoperative position, as shown, within the hood 6. With the parts in this condition, the iron is used 10 in the normal manner.

When it is desired to use the supporting device, pressure is applied to the finger portion 33 of the actuating device 32, thus moving the lever 29 in a counter-clockwise direction, as viewed in 15 Fig. 1, against the action of spring 35. This causes the arm 26 to be pulled upward and the crank 25 therefore rotates shaft 12 in a clockwise direction, as viewed in Fig. 1. As the shaft 12 rotates, it carries arms 17 with it and, therefore, 20 the crank pins 24 are caused to move in the stationary slot 15. The pins 24 ride upward through the curved slots until they reach the transverse portions 16 of the slots. At such time, the slots cam the cranks 23, the pins 24 moving into the 25 transverse slot portions 16, thus causing rotation of the small cranks 23 and effecting rotary movement of the arms 17 relative to shaft 12. The free end portions of arms 17 are thus moved from their folded positions shown to the positions 30 illustrated in broken-line representation in Fig. 1. Thus, in their operative positions, the arms 17 are disposed longitudinally of the iron and below the same and are adapted to support the iron in well-known manner. The arms 17 are 35 preferably arranged so that they extend at a slight angle relative to the iron, so that the iron is slightly tilted upward toward its front end when the arms 17 rest on a horizontal surface.

It will be seen that there are two distinct movements of the arm 17 involved in the operation 40 of the mechanism. The arms are movable bodily about the axis of shaft 12 as a pivot to swing the arms in an arc from the horizontal position shown in Fig. 1 and, at the same time, the arms are 45 movable rotatably with respect to shaft 12 to move their free ends from the folded position to the extended operative position.

When the supporting device moves to operative position as above described, the flat extensions 50 22 engage the rear part of the sole plate and serve to brace the device and to distribute the strain due to the weight of the supported iron. As long as the iron rests upon the extended supporting arms, the device is prevented from 55 moving to inoperative position. In other words, the weight of the iron maintains the supporting arms in their operative positions against the action of spring 35. As soon as the iron is lifted, however, the spring 35 causes the parts to 60 return to the position shown in a manner which will be obvious from the above description. Thus, the supporting arms 17 are moved automatically to inoperative position within the hood 6 upon the mere lifting of the iron. The actuating device 32 65 is used only to move the supporting arms to operative position, as above described.

From the illustration and above description, it will be seen that the supporting arms are disposed at the rear of the iron when the supporting 70 device is not being used, so that this device can in no way interfere with the use and functioning of the iron. Furthermore, it will be seen that the supporting device is invisible when in its inoperative condition, so that it does not detract 75 from the appearance of the iron. It will be un-

derstood, of course, that the invention is not limited to the specific embodiment illustrated but is capable of various modifications without departing from its scope.

5

I claim:

1. In combination with a flat-iron having an ironing surface, supporting means carried by the iron comprising arms movable into inoperative position transversely of the iron above the plane of said ironing surface and into operative position longitudinally of the iron below the plane of said ironing surface, and manually operable means for actuating said supporting means.

10

2. In combination with a flat-iron having an ironing surface, supporting means carried by the iron comprising arms movable into inoperative position transversely of the iron above the plane of the iron surface and at the rear thereof and into operative position longitudinally of the iron below the same, and manually operable means 20 for actuating said supporting means.

15

3. In combination with a flat-iron, a hood carried by and extending from the body of said iron, supporting means carried by the flat-iron comprising a plurality of supporting members movable into said hood into crossed relation and movable out of the hood into extended cooperative relation, and manually operable means for actuating said supporting means.

25

4. In combination with a flat-iron having an ironing surface, a downwardly opening hood carried by the flat-iron above the plane of said ironing surface, supporting means carried by the iron comprising arms movable into inoperative position transversely of the iron within said hood and into operative position longitudinally of the iron below the plane of said ironing surface, and manually operable means for actuating said supporting means.

30

5. In combination with a flat-iron having an ironing surface, supporting means carried by the iron movable into inoperative position transversely of the iron above the plane of said ironing surface and into operative position longitudinally of the iron below the plane of said ironing surface, and manually operable means for actuating said supporting means.

40

6. In combination with a flat-iron having an ironing surface, supporting means for the iron, comprising a transverse rotatable shaft carried 50 at the rear of said iron and a pair of arms extending transversely of said shaft and having portions rotatably disposed on axes transverse with respect to that of the shaft, whereby the arms are rotatable with the shaft and are also rotatable relative to the shaft, said arms being bent to provide angularly extending feet portions, means for rotating said shaft, and means for causing rotary movement of said arms relative to said shaft when the shaft is rotated, said means being arranged and adapted to move said feet portions into inoperative position transversely of the iron above the plane of said ironing surface and into operative position longitudinally of the iron below the plane of said ironing surface.

55

7. In combination with a flat-iron having an ironing surface, supporting means for the iron, comprising a transverse rotatable shaft carried at the rear of said iron and a pair of arms extending transversely of said shaft and having portions rotatably disposed in transverse openings of the shaft, whereby the arms are rotatable with the shaft and are also rotatable relative to the shaft, said arms being bent in a substantially right angular form to provide feet portions,

60

65

70

75

means for rotating said shaft, a crank carried by each of said arms, and stationary cam means cooperatively associated with each said crank to rotate said arms relative to said shaft when the shaft is rotated, said cam means being arranged and adapted to move said feet portions into inoperative position transversely of the iron above the plane of said ironing surface and into operative position longitudinally of the iron below the plane of said ironing surface.

8. In combination with a flat-iron having an ironing surface, a downwardly opening hood carried by said iron at the rear thereof, supporting means for the iron, comprising a transverse rotatable shaft mounted within said hood and a pair of arms extending transversely of said shaft and having portions rotatably disposed on axes

transverse with respect to that of the shaft, whereby the arms are rotatable with the shaft and are also rotatable relative to the shaft, said arms being bent in a substantially right angular form to provide feet portions, means for rotating said shaft, a crank carried by each of said arms, and cam means cooperatively associated with each said crank to rotate said arms relative to said shaft when the shaft is rotated with respect to the cam means, said cam means being arranged and adapted to move said feet portions into inoperative position transversely of the iron above the plane of said ironing surface and into operative position longitudinally of the iron below the plane of said ironing surface.
